(57) **CLAIM**

The ornamental design for a dual overlap catheter anchor pad with release layers, as shown and described.

DESCRIPTION

FIG. 1 is a perspective view of the dual overlap catheter anchor pad with release layers, shown in a spread position with two portions of the upper release layer slightly separated from the underlying adhesive layer.

FIG. 2 is a top view of the dual overlap catheter anchor pad with release layers.

FIG. 3 is a bottom view of the dual overlap catheter anchor pad with release layers.

FIG. 4 is a front view of the dual overlap catheter anchor pad with release layers, the rear view being a mirror image; and, FIG. 5 is a right side view of the dual overlap catheter anchor pad with release layers, the left side view being a mirror image.
